UNITED STATES PATENT OFFICE.

EFRAIM LUNDIN, OF BOSTON, MASSACHUSETTS, ASSIGNOR OF THREE-FOURTHS TO MARIO L. FELKIN, OF BOSTON, MASSACHUSETTS.

STREET OR STATION INDICATOR.

SPECIFICATION forming part of Letters Patent No. 738,464, dated September 8, 1903.

Application filed February 24, 1903. Serial No. 144,583. (No model.)

To all whom it may concern:

Be it known that I, EFRAIM LUNDIN, a subject of His Majesty the King of Sweden and Norway, and a resident of Boston, in the county of Suffolk and State of Massachusetts, have invented new and useful Improvements in Street or Station Indicators, of which the following is a specification.

My invention relates in general to automatic street or station indicators for railway-cars, and particularly to that class of indicators that are operated by an electric motor in a circuit controlled by a wheel traveling on the road over which the cars pass.

The main feature of my improved indicator for railway-cars is that two switches are provided in the circuit of the motor which operates the announcing mechanism, and one of these switches is closed to start the motor each time the announcing mechanism is to be operated and the other switch is automatically opened to stop the motor after the announcing mechanism has been operated to the required predetermined extent through the closing of the first switch. Thus in my improved indicator the motor is normally at rest and is only operated when the announcing mechanism is to be operated, and the announcing mechanism is moved to the same extent each time it is operated. I am therefore enabled to arrange the inscriptions of the announcing mechanism equidistant on the traveling surface, as well as to economize in the length of traveling surface employed. These results are among the objects of my invention; and it is also an object of my invention to generally improve the construction of street or station indicators of this class.

Other features of my invention are herein-after pointed out.

In the accompanying drawings, Figure 1 is an elevation of the station-announcing mechanism. Fig. 2 is a section on line 2 2 of Fig. 1. Fig. 3 is a section on the line 3 3 of Fig. 2. Fig. 4 is a detail of one of the spring-actuated rolls. Fig. 5 is an elevation, partly in section, of the wheel and coöperating mechanism hereinafter described for starting the motor. Fig. 6 is a section on line 6 6 of Fig. 5. Fig. 7 is a detail hereinafter described. Fig. 8 is

a diagrammatical view showing the circuits and main elements of my improved street or station indicator.

Having reference to the drawings, the street or station announcing mechanism is shown in Figs. 1, 2, and 3 and is placed, as usual, within a car in position to be visible to the occupants thereof. The mechanism itself is arranged within a casing or housing A, made with openings a, through which traveling sheets a', having the names of the stations inscribed thereon, are visible. Herein I have shown six openings a and six traveling sheets a'. Each sheet a' is supported by a number of rolls that are journaled in a separate frame a², removably secured within the housing A. The sides A' of the casing A are also made removable in any suitable manner, so that frames a² may be withdrawn from the casing A. The object of making the frames a² removable is that when the route over which the car is to travel is changed the frames already in position may be removed and replaced by other frames carrying sheets a' properly inscribed for the new route. One end of each sheet a' is fastened to a roll a³, and the other end is fastened to a similar roll a⁴. Each roll a³ and a⁴ is hollow, (see Fig. 4,) and within the same is arranged a rubber strap a⁵, fastened at one end to the roll and at its other end to a fixed part on frame a². Herein this fixed part is shown as a stud a⁶, fixed to frame a² by means of a clamping-nut on the outer end of each stud a⁶. Each sheet a' extends from its roll a³ between a pair of rolls a⁷ and a⁸ and thence downwardly past its opening a between a similar pair of rolls a⁷ a⁸ and then to its roll a⁴. Each roll a⁸ carries at one end a worm-gear a⁹, driven by a worm a¹⁰, fast on shaft a¹¹, mounted in bearings on casing or housing A. Each shaft a¹¹ carries at its upper end a sprocket a¹², driven by a chain a¹³, which in turn is driven by a sprocket a¹⁴. The sprocket a¹⁴ is connected with a gear a¹⁵, and both gear a¹⁵ and sprocket a¹⁴ are journaled on a stud fixed to the housing A. Gear a¹⁵ is driven by a pinion b, fixed to the armature-shaft of an electric motor B, and said shaft also carries a worm b', which drives a worm-gear b², fixed to an arbor b³. The arbor b³ is journaled in

posts fixed to housing A and carries a disk of insulating material b^4 , on which is mounted a fixed contact member or electrode b^5 and a peripheral ring b^6 . To the ring b^6 is pivoted 5 a movable contact member b^7 , adapted to contact with the member b^5 . Pivoted member b^7 is acted upon by two springs b^8 , which tend to hold said member in contact with member b^5 .

Mounted upon the under side of the body 10 of the car is a casing C, within which is arranged a frame c. In bearings on frame c is journaled a shaft c', carrying a drum c², and on one end of said shaft is mounted a worm-gear c³. The gear c³ is driven by a worm c', fixed to one end of a shaft c⁵, to the opposite 15 end of which is fixed a wheel c⁶, adapted to travel on the road over which the car is passing. Rotation of wheel c⁶ acts through worm c⁴ to rotate gear c³ and drum c². Drum c² is provided with a spiral row of pins c⁷, one end 20 of which row is at one end of drum c² and the other end thereof at the opposite end of said drum. Alongside the drum c² is a screw-shaft c⁸, journaled at its ends in the frame c and 25 carrying at one end a pinion c⁹, driven by the gear c³. On screw c⁸ is mounted a switch-carrier c¹⁰, carrying a movable contact member D and two spring contact members d, and said carrier is moved by screw c⁸ sidewise longitudinally of drum c² in one direction when 30 the car is traveling in one direction and in the opposite direction when the car is traveling in the opposite direction. One end of the switch-carrier c¹⁰ is mounted to slide 35 on a guide-rod c¹¹, fixed at its ends to the frame c, so that carrier c¹⁰ is rigidly supported. The relative speeds of screw c⁸ and drum c² are such that contact member D on the inner end of the carrier c¹⁰ when started at one end 40 of the spiral row of pins c⁷ will be caused to traverse that row and contact with every pin in it. Each pin c⁷ represents a station on the route, and by properly spacing the pins of the spiral row and locating each pin in its 45 proper place on the drum each pin will operate member D at a time during the travel of the car over its route when the car reaches the point on its route at which it is desired to announce the station represented by that 50 pin. In other words, the row of pins c⁷ represents the route of the car and each pin c⁷ a station on that route, and the sidewise movement of switch-carrier c¹⁰ and the rotary movement of drum c² are such that the contact member D, mounted on carrier c¹⁰, is caused to traverse the spiral row of pins c⁷ at 55 the same relative rate of speed as the car is traveling over its route. One contact member d is connected by a wire d' with one set 60 of armatures of a motor B, and the other spring contact member is connected by a wire d² with another set of armatures of the motor B. (See Fig. 8.) Motor B is connected by a wire d³ with the fixed contact member b⁵, carried by disk b⁴, and the peripheral ring b⁶ is

in contact with a spring-finger d⁴, connected by a wire d⁵ with the ground. The contact member D is connected by a wire d⁶ with any source or supply of electrical energy—as, for instance, with the trolley-wire of the road. 70

It will be seen now that when contact member D is engaged by a pin c⁷ traveling in one direction said member is thrown into contact with one of the contact members d and a circuit is closed through one set of armatures of motor B, and when contact member D is engaged by a pin c⁷ traveling in the opposite direction said member contacts with the other member d and a circuit is closed through the other set of armatures of motor B. The engagement of contact member D with either one of the contact members d thus starts the motor B in operation, but in one direction when member D is operated by the pins traveling in one direction and in the opposite direction when member D is operated by the pins traveling in the opposite direction. 75 80 85

When motor B is set in operation in either direction, as above described, the pinion b, carried by its armature-shaft, rotates gear a¹⁵ 90 and sprocket a¹⁴, which, acting through the chain a¹³ and sprocket a¹⁴, rotates the two shafts a¹¹. The two shafts a¹¹ when actuated act through the worms a¹⁰ and worm-gears a⁹ to rotate the rolls a⁸, which act to positively 95 draw the sheets a' from one roll a³ or a⁴, thus winding up the band a⁵ of that roll, allowing the other end of the sheet to be automatically wound upon the other roll a³ or a⁴ by the band a⁵ of that roll as it unwinds. 100

In order that the sheets a' shall be moved to the same extent at each operation and only far enough to carry one inscription past its opening a and to present the next inscription, a movable stop b⁹ is provided, mounted on an armature b¹⁰, that is operated by a magnet b¹¹. One end of the coil of magnet b¹¹ is connected by a wire b¹² with a pair of electrodes or contact members b¹³, mounted on carrier c¹⁰. One contact member b¹³ coöperates with one contact member d, and the other member b¹³ coöperates with the other contact member d. When either contact member d is engaged by the movable member D, it is bent slightly, so that it is not only in contact with member D, but with member b¹³ also. The other end of the coil of magnet b¹¹ is connected by a wire b¹⁴ with the wire d⁵. Normally stop b⁹ is held out of the path of pivoted member b⁷ by a spring b¹⁵, but when a pin c⁷ operates member D and one of the members d is caused to contact with one of the contacts b¹³ a shunt-circuit is closed 110 through the magnet b¹¹, which operates its armature and throws stop b⁹ against the end 115 of pivoted member b⁷. At the same time a circuit is closed through motor B, and the operation of motor B carries the pivoted member b⁷ away from stop b⁹, which is then moved 120 farther forward by magnet b¹¹ behind the 125 130

outer end of pivoted member b^7 . When disk b^4 nearly completes one revolution, the outer end of pivoted member b^7 is brought around against the stop b^9 , then in its path, and the continued movement of disk b^4 causes member b^7 to be swung on its pivot until its inner end is moved out of contact with the fixed contact member b^5 , carried by disk b^4 . This breaks the circuit through motor B and stops its operation. Stop b^9 , however, remains in the path of the outer end of pivoted member b^7 until the pin c^7 frees contact member D, which not only makes a second break at D in the circuit of motor B, but also opens the shunt-circuit through magnet b^{11} , whereupon armature b^{10} is swung back by spring b^{15} far enough to carry stop b^9 out of engagement with the end of pivoted member b^7 , which is then swung back into contact with fixed contact member b^5 by one of the springs b^8 . This carries the outer end of pivoted member b^7 into the path of stop b^9 , and the operation is repeated when the next pin c^7 engages member D.

It will now be observed that when the direction of travel of the car is reversed the direction of rotation of drum c^2 and the direction of sidewise movement of carrier c^{10} is reversed and that this results in the reversal of the motor B and disk b^4 , as well as of the announcing mechanism, which is actuated by said motor. Pivoted member b^7 and stop b^9 coöperate, as above described, for either direction of movement of disk b^4 . Thus the operation of the announcing mechanism within casing A is automatically reversed when the direction of travel of the car is reversed.

The motor herein represented is of that type having two sets of armatures so arranged that when one set is in operation the armature-shaft is driven in one direction and when the other set is in operation the armature-shaft is driven in the opposite direction. If desired, however, any other arrangement of motor or motors may be substituted in lieu of that herein shown that will be controlled by the double-acting switch or carrier c^{10} without departing from the spirit and scope of my invention.

When the route over which the car is to travel is changed, the frames a^2 are removed, as above described, and others substituted which are properly inscribed for the new route, and, as will be obvious, it is also necessary to substitute another drum c^2 , having pins c^7 , that are spaced to accord with the stations on the new route. For this reason the frame c^2 is removably mounted within casing C, so that by removing one of the sides of the casing C the frame c may be removed and another substituted which is appropriate to the new route.

Of course without material change my invention may be adapted to the display of advertisements, and in this connection it will be

obvious that it may be used on other vehicles than railway-cars.

What I claim is—

1. In a device of the character indicated, in combination, announcing mechanism; a motor for operating the announcing mechanism; a switch in the circuit of said motor; means for intermittently closing said switch to start the motor; a second switch in the circuit of said motor, and means operated by said motor when its circuit is closed through the first switch for automatically opening the second switch to stop the motor after the latter has operated to a predetermined extent. 70
2. In a device of the character described, in combination, announcing mechanism; a motor for operating the announcing mechanism; a normally open switch in the circuit of said motor; means for intermittently operating said switch to intermittently start the motor; a second normally closed switch in the circuit of said motor, and means operated by said motor when its circuit is closed through the first switch for automatically operating the second switch alternately with relation to the operations of the first-mentioned switch so as to stop the motor after the latter has operated to a predetermined extent. 80
3. In a street or station indicator, in combination, street or station announcing mechanism; a motor for actuating the announcing mechanism; a circuit in which said motor is arranged; a switch in said circuit; a wheel on which said switch is mounted; means connecting the wheel and motor; a stop for operating the switch; and automatic means for operating the stop. 90

4. In a street or station indicator, in combination, street or station announcing mechanism; a motor for actuating the announcing mechanism; a circuit in which said motor is arranged; a switch in said circuit; a wheel on which said switch is mounted; means connecting the wheel and motor; a shunt-circuit 100 around the motor; a magnet in the shunt; an armature controlled by the magnet; a stop controlled by the armature for operating the switch on the wheel; and means for intermittently operating the motor-circuit. 105

5. In a street or station indicator, in combination, street or station announcing mechanism; a pair of motor-circuits; a motor in both of said circuits for actuating the announcing mechanism; a switch in said circuits; a wheel on which said switch is mounted; means connecting the wheel and motor; a shunt-circuit for each motor-circuit; a magnet in both shunts; an armature controlled by the magnet; a stop controlled by the armature for operating the switch on the wheel; means operated by the car traveling in one direction to intermittently close one motor-circuit and shunt, and means operated by the car traveling in the opposite direction to 130 intermittently close the other motor-circuit and shunt. 125

6. In a street or station indicator, in combination, street or station announcing mechanism; a pair of motor-circuits; a motor in said circuits for actuating the announcing mechanism; a switch for controlling said circuits; a wheel on which said switch is mounted; means connecting the wheel and motor; a shunt-circuit for each motor-circuit; a magnet in both shunts; an armature controlled by the magnet; a stop controlled by the armature for operating the switch on the wheel; a double-acting switch for controlling the two

motor-circuits; and means operated by the travel of the car for intermittently operating said switch to close one motor-circuit when the car is traveling in one direction and to close the other motor-circuit when the car is traveling in the opposite direction. 15

Signed by me at Boston, Massachusetts, this 20th day of February, 1903.

EFRAIM LUNDIN.
